RECTIFIER

Application filed October 21, 1927, Serial No. 227,654, and in Germany November 1, 1926.

This invention relates to improvements in rectifiers of the metal vapour type, and more particularly to the construction and arrangement of the cooling means for the anodes thereof.

5 It is common practice in metal vapour rectifier construction to provide cooling means for the purpose of limiting the maximum temperature attained by the anodes so that the valve action is maintained and the tendency for occurrence of back-ignition is substantially reduced. Such cooling means has heretofore consisted of a water jacket disposed about the inactive part of each anode, 10 the amount of heat carried off depending on the rate of circulation of the cooling water through the jacket and the radiating effect of the latter. With respect to such radiating effect, it has been found and recognized that 15 the same is increased substantially by giving to the cooling jackets such form and relative disposition as to induce appreciable draught or movement of the air in their vicinity to accordingly make as high as possible the 20 coefficient of heat transmission or radiation, this coefficient being the constant representing the number of calories passing from the radiating surface of the cooling jacket to the surrounding air per unit of time, per unit area 25 of radiating surface, per degree centigrade difference between the respective temperatures of the radiating surface and the surrounding air. It has been proposed to arrange the cooling jackets, in rectifiers constructed heretofore, in such manner that adjacent jackets are spaced from each other in 30 such manner that the spaces between the same provide ventilating chimneys which act to induce draught and consequent movement of the surrounding cooling air. In 35 these prior constructions, the cooling jackets have been circular or oval in cross section, and have only been effective to provide for a relatively low coefficient of heat transmission for the reason that their cross section provides for only a very limited portion of 40 their adjacent surfaces being in close proximity to form the ventilating chimneys. Jackets of this type used heretofore, further- 45 more, when associated or used with anodes ar-

ranged in circular formation, have the additional serious disadvantage in that they inadequately utilize the available space.

One of the objects of the present invention, therefore, is to provide an improved rectifier wherein the cooling jackets for the anodes thereof are so shaped and arranged as to provide for a comparatively high coefficient of heat transmission while at the same time permitting of better utilization of the available space in cases such as when the anodes are arranged in circular formation.

Other objects and advantages will herein-after appear.

According to the present invention, the cooling jackets for the anodes are made wedge-shape in cross section to permit of better utilization of the available space and the provision of more efficient ventilating chimneys between adjacent jackets than has been possible heretofore. When the anodes are arranged in circular formation, the narrow or thin edges of the jackets are directed inwardly toward the center, the cross section and taper of the jackets being so chosen that the flat adjacent surfaces of the jackets are in sufficiently close proximity to each other to provide chimneys having a high ventilating or draught effect. In cases where the anodes are arranged in two concentric circles, the cooling jackets in both circles are similarly arranged with their narrow edges directed inwardly toward the center, or as an alternative, the cooling jackets associated with the anodes in the outer circle are arranged with their narrow edges directed inwardly while the jackets associated with the anodes in the inner circle are arranged with their narrow edges directed outwardly so that when the number of anodes in each circle is the same and the anodes in the two circles arranged in staggered relation, the inner and outer wedge-shaped cooling jackets interfit with each other to provide the ventilating chimneys between adjacent jackets.

For the purpose of illustrating the invention, several embodiments thereof have been shown in the drawings wherein

Figure 1 is an outline plan view of a recti-

fier embodying the present improvements; and

Fig. 2 is a view similar to Fig. 1, showing a modification.

- 5 In Fig. 1, reference characters $a_1, a_2, a_3, \dots, a_{12}$ denote the twelve anodes of a metal vapour rectifier arranged in circular formation in the top plate or cover b thereof, each anode being surrounded, as indicated, by a cooling jacket 10 of wedge-shape cross section, the jackets being so arranged that the narrow edges thereof or, in other words, the narrow ends of the sections are directed inwardly toward the center, the respective jackets being designated by the reference characters $c_1, c_2, c_3, \dots, c_{12}$. The distance d between the adjacent flat surfaces of the jackets is relatively small, as indicated, the opposite or adjacent flat surfaces being parallel to form an efficient ventilating chimney capable of giving a strong vertical draught, and accordingly providing for a coefficient of heat transmission of the jackets or cooling means which is substantially higher than such coefficient of the cooling jackets used heretofore and referred to above.

- 25 In Fig. 2, twelve anodes are also shown, the anodes, however, being arranged in two concentric circles with the anodes a_1 to a_6 in the inner circle equal in number to and arranged in staggered relation with respect to the anodes a_7 to a_{12} in the outer circle. In the arrangement as shown in Fig. 2, the cooling jackets c_1 to c_6 associated with the inner anodes are arranged with the narrow ends of their wedge-shaped sections directed outwardly, while the jackets c_7 to c_{12} associated with the outer anodes are arranged with the narrow ends of their wedge-shaped sections directed inwardly whereby the respective inner and outer jackets interfit with each other to provide ventilating chimneys between their adjacent flat surfaces.

30 By employing the arrangement of Fig. 2, the space occupied by the cooling jackets in the direction of the center of the anode plate b is appreciably reduced, the diameter of the inner anode circle being therefore also reduced correspondingly to give a more compact design for the whole rectifier.

35 45 50 From the foregoing, it will be seen that an improved rectifier has been provided having cooling means for the anodes thereof which provides for compact arrangement and a substantially higher coefficient of heat transmission of the cooling means than has been present or in fact possible in constructions used heretofore.

55 60 Several embodiments of the invention have been shown and described, but of course various changes might be made without departing from the spirit of the invention or the scope of the claims.

The invention claimed is:

- 65 1. In a metal vapour rectifier, a supporting plate, anodes circularly mounted thereon, and

cooling jackets disposed about said anodes and being of wedge-shape cross section to provide flat angularly disposed radiating surfaces, certain of said jackets being mounted with the narrow ends of such sections directed inwardly toward the center of said plate, adjacent jackets being mounted with their respective flat surfaces disposed opposite each other in relatively close proximity to form ventilating chimneys between the adjacent jackets.

2. In a metal vapour rectifier, a supporting plate, anodes mounted on said plate in two substantially concentric circles, the respective anodes in the outer and inner circles being mounted in staggered relation, and cooling jackets disposed about said anodes and being wedge-shape in cross section, the jackets surrounding the outer anodes being mounted with the narrow ends of such sections directed inwardly toward the center of said plate, the jackets surrounding the inner anodes being mounted with such sections directed outwardly from said center, said jackets being arranged with their respective adjacent surfaces in relatively close proximity to form ventilating chimneys between the adjacent jackets.

3. The combination with a metal vapour rectifier having anodes, of cooling jackets wedge-shape in cross section disposed about said anodes and mounted with their respective adjacent surfaces in relatively close proximity to form ventilating chimneys between the adjacent jackets.

In testimony whereof I have hereunto subscribed my name this 7 day of October, A. D. 1927.

MAX SCHIESSEER.
